TYRUS McCARGAR, OF MASONVILLE, IOWA, ASSIGNOR TO HIMSELF AND
SIMEON P. PETERS, OF SAME PLACE.

Letters Patent No. 105,104, dated July 5, 1870.

IMPROVEMENT IN SPRING-CATCH BOLT.

The Schedule referred to in these Letters Patent and making part of the same

To all whom it may concern:

Be it known that I, TYRUS McCARGAR, of Masonville, Delaware county, in the State of Iowa, have invented a new and Improved Spring-catch Bolt; and I hereby declare the following to be a full and exact description thereof, reference being had to the accompanying drawing forming part of this specification.

The nature or essence of my invention consists in providing a bolt for connecting separate pieces by passing through them, or for other purposes, with a spring-catch welded to the head of the bolt, so as to be in one piece with it, and extending along in the same direction with the bolt, so as to catch over some one of the pieces which the bolt passes through.

In the drawing hereinbefore mentioned—

Figure 1 is a top view of a carriage-thill iron and a clip, connected by my improved bolt;

Figure 2 is a side view of the same; and

Figure 3, a view of the bolt.

The bolt A has the spring B welded to its head and extended along parallel or nearly parallel with the bolt toward the opposite end of the same, said spring being provided with a catch, C, beveled on its front or outer side, but forming a shoulder by its inner side at right angles to the direction of the bolt or spring.

When the bolt is put through the pieces which it is to connect, the beveled side of the catch meeting said pieces is forced back or lifted somewhat until the bolt is through or in place, and then the catch will spring down over the edge of the piece passed through, and thus secure the bolt in its place.

To disconnect the parts again, it is only necessary to raise or draw back the spring-catch with the finger, when the bolt can be readily drawn out.

This device is recommended by its extreme simplicity, its cheapness and durability, and its freedom from liability to be clogged with mud or ice, so as to make it inconvenient to remove it when required.

What I claim, and desire to secure by Letters Patent, is—

The combination, with the bolt A, of the spring B, provided with a catch, C, when welded to the head of the bolt so as to be in one piece therewith, and extended along toward the opposite end of the same, substantially as and for the purpose herein set forth.

TYRUS McCARGAR.
